UNITED STATES PATENT OFFICE.

JOSEPH FELLEY, OF PATERSON, NEW JERSEY.

MOTOR-SKATE.

1,164,798.

Specification of Letters Patent. Patented Dec. 21, 1915.

Application filed April 3, 1914, Serial No. 829,317. Renewed August 17, 1915. Serial No. 46,014.

To all whom it may concern:

Be it known that I, JOSEPH FELLEY, a citizen of the United States, residing at Paterson, in the county of Passaic and State of New Jersey, have invented new and useful Improvements in Motor-Skates, of which the following is a specification.

This invention relates to motor skates, the object of the invention being to produce a device of the class described embodying novel driving mechanism whereby the whole weight of the operator may be utilized for propelling the skate.

A further object of the invention is to provide in combination with the frame of the skate, and driving means, brake mechanism arranged for convenient operation and not acting directly on either driving or steering wheel of the skate thus saving the tires and front and rear wheel bearings.

With the above and other objects in view, the invention consists in the novel construction, combination and arrangement of parts, as will hereinafter be more fully described, illustrated and claimed.

In the accompanying drawings:—Figure 1 is a side elevation of a skate embodying the present invention. Fig. 2 is a vertical longitudinal section illustrating the arrangement of parts of the driving mechanism. Fig. 3 is a vertical cross section through the skate on the line 3—3 of Fig. 1. Fig. 4 is a similar section on the line 4—4 of Fig. 1. Fig. 5 is a detail perspective view of the drop frame.

The main frame of the skate comprises substantially parallel top runs 1 arranged in spaced relation to each other as shown in Figs. 3 and 4 and connected at their forward ends to the front fork members 2 and at their rear ends to the rear fork members 3, 4 designating the front driving wheel of the skate and 5 the rear steering wheel thereof, the wheel 4 being mounted in the fork 2 and the wheel 5 being mounted in the fork 3.

Combined with the main frame thus far described is a drop frame comprising front and rear relatively spaced downwardly extending members 6 which are connected at their lower ends by a bottom support 7, the drop frame referred to being further supported by the braces 8 which extend from the bottom 7 thereof upwardly to a head tube 9 in which is journaled the spindle of the rear fork 3 thus enabling said rear

wheel 5 to be turned to one side or the other for steering the skate.

Operating above the bottom 7 of the drop frame is a vertically movable platform 12 upon which the operator's foot is adapted to be placed. The platform 12 is provided with a downwardly extending post 15 which is slidable through a sleeve 16 extending vertically through the bottom 7 of the drop frame and having a fixed relation thereto. Surrounding the post 15 is a coiled expansion spring 17 of sufficient strength to lift the platform 12 when relieved of the weight of the rider's feet, the upward movement of the platform 12 being limited by projections 18 on the platform 12 working in slots 18' in the members 6 of the drop frame.

The front driving wheel 4 is provided at opposite sides thereof with spur gear wheels 19 which mesh with and are driven by other spur gear wheels 20 journaled on a cross shaft 21, each of said wheels 20 being provided with a brake drum 22 the purpose of which will hereinafter appear.

Journaled on the opposite ends of the shaft 21 are levers 23 which extend beyond the peripheries of the wheels 20 and have pivotally connected thereto at 24 links 25 which are pivotally attached at 26 to the vertically movable platform 12. Each of the levers 23 carries a stud shaft 27 on which is journaled one of a pair of oppositely arranged double faced pinions 28, each pinion comprising a spur gear face 29 which meshes with one of the wheels 20 and in addition thereto a ratchet face 30 which is engaged by a detent 31 on the adjacent lever 23 thereby permitting said double faced wheel to turn in one direction only and that is when the lever 23 is moved upwardly. When the lever 23 moves downwardly, the said pinion is locked against rotation and therefore carries the periphery of the wheel 20 with it. In this way motion is imparted to the front driving wheel 4.

32 designates a U-shaped brake lever embodying two arms which extend downwardly on opposite sides of the main frame of the skate and are pivotally connected at 33 to the bottom 7 of the drop frame. From the arms of said brake lever 32 rods 34 extend forwardly where they are provided at their forward extremities with brake bands 35 which work in contact with the brake drums 22 hereinabove referred to. The arms of the lever 32 are connected at the top by a

cross bar 36 within convenient reach of the operator who by pushing rearwardly thereon may apply the brakes. Springs 37 connect with the lever arms 32 and serve to hold the brakes normally out of engagement with the drums 22.

10 A foot holding strap 38 is secured to extensions 40 on the vertically movable platform 12 so that the foot of the rider is securely held to the platform and he is enabled to raise said platform assisted by the spring 17. The platform 12 may also if desired be provided with side and end flanges 41 and 42, respectively, to assist in holding 15 the rider's feet firmly thereon.

From the foregoing description it will now be understood that the rear wheel of the 20 skate is used as the steering wheel and the driving mechanism connects with the front wheel, said driving mechanism being primarily actuated by an upwardly spring 25 thrust platform which is compressible by the foot of the operator who may thereby impose his full weight on the platform for the purpose of propelling the skate.

The brake mechanism is not associated directly with the tires or front and rear supporting wheels of the skate but only indirectly with said wheels through the medium 30 of the intermediate spur gear wheels 20 which carry the brake drums 22.

It will be understood that two of such 35 skates are ordinarily used by the operator, one skate being strapped to each foot, the operator pressing alternately on one or the other of the skates and thereby actuating the driving mechanism hereinabove described. This enables the operator to propel himself 40 rapidly from place to place by simply imposing his weight alternately upon each of the pair of skates.

What I claim is:—

1. A motor skate comprising a main frame, embodying parallel top runs in spaced relation to each other, a front driving wheel and a rear steering wheel supporting said main frame, a drop frame bearing

a fixed relation to said main frame, a spring elevated compressible platform for the operator's foot supported above and by the lower 50 part of said drop frame, driving mechanism actuated by the vertical movement of said platform for imparting motion to said front driving wheel, said driving mechanism comprising a spur gear wheel on said driving 55 wheel, a second spur gear wheel meshing therewith, a lever journaled on the shaft of the last named wheel, a link connecting said lever and platform, a spur pinion journaled on said lever and meshing with the 60 last named wheel, and pawl and ratchet elements permitting said pinion to turn in one direction only.

2. A motor skate comprising a main frame, embodying parallel top runs in spaced 65 relation to each other, a front driving wheel and a rear steering wheel supporting said main frame, a drop frame bearing a fixed relation to said main frame, a spring elevated compressible platform for the operator's foot supported above and by the lower part of 70 said drop frame, driving mechanism actuated by the vertical movement of said platform for imparting motion to said front driving wheel, said driving mechanism comprising a spur gear wheel on said driving 75 wheel, a second spur gear wheel meshing therewith, a lever journaled on the shaft of the last named wheel, a link connecting said lever and platform, a spur pinion journaled 80 on said lever and meshing with the last named wheel, and pawl and ratchet elements permitting said pinion to turn in one direction only, a brake drum on the last named gear wheel, a brake band, and a brake lever 85 pivotally mounted on said drop frame and connected with said brake band.

In testimony whereof I affix my signature in presence of two witnesses.

JOSEPH FELLEY.
